United States Patent Office

Des. 214,471
Patented June 17, 1969

214,471

DISPLAY PANEL FOR FOODS OR THE LIKE

Benjamin B. Lavin and Paul B. Dixson, Canton, Ohio, and Robert G. Hammond, New York, N.Y., assignors to Sugardale Foods, Inc., Canton, Ohio, a corporation of Ohio

Filed May 6, 1968, Ser. No. 11,787

Term of patent 14 years

Int. Cl. D20—02; D6—01

U.S. Cl. D80—1

Fig. 1

Fig. 3

Fig. 2

We claim:

The ornamental design for a display panel for foods or the like, as shown.
